CLAIM

The ornamental design for a care apparatus, as shown and described.

DESCRIPTION

FIG. 1 is a perspective view of a care apparatus showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is another perspective view thereof.

The broken lines in the drawings depict parts of the care apparatus that form no part of the claim.

1 Claim, 8 Drawing Sheets
